(12) **United States Design Patent** (10) Patent No.: **US D1,030,051 S**
(45) Date of Patent: ** Jun. 4, 2024

(54)	SYRINGE PLUNGER	1,950,137 A	3/1934	Dowe
(71)	Applicant: Bayer HealthCare LLC , Whippany, NJ (US)	1,988,480 A	1/1935	Campkin
(72)	Inventors: Kevin Cowan , Allison Park, PA (US); John Haury , Sewickley, PA (US)	2,392,196 A	1/1946	Smith
(73)	Assignee: Bayer Healthcare LLC , Whippany, NJ (US)	2,419,401 A	4/1947	Hinds
(**)	Term: 15 Years	2,702,547 A	2/1955	Glass
(21)	Appl. No.: 29/902,166	2,842,126 A	7/1958	Brown
(22)	Filed: Sep. 8, 2023	3,051,173 A	8/1962	Johnson et al.
	Related U.S. Application Data	D203,730 S	2/1966	Porat
(60)	Continuation of application No. 29/751,090, filed on Sep. 18, 2020, now Pat. No. Des. 1,002,840, which is a continuation of application No. 16/946,008, filed on Jun. 2, 2020, now abandoned, which is a continuation of application No. 15/851,860, filed on Dec. 22, 2017, now Pat. No. 10,668,221, which is a continuation of application No. 14/576,354, filed on Dec. 19, 2014, now Pat. No. 9,855,390, which is a division of application No. 11/686,000, filed on Mar. 14, 2007, now Pat. No. 8,926,569.	3,270,483 A	9/1966	Smoyer et al.
